UNITED STATES PATENT OFFICE.

MARY V. BRUNK AND DAISY D. HARRISON, OF KANSAS CITY, KANSAS.

FROCK.

Application filed August 9, 1926. Serial No. 128,160.

Our invention relates to frocks and one object of the invention is to provide a frock with detachable sleeves and collar which can be easily removed when it is desired to 5 wear the frock without these parts.

A further object is to form the sleeves and the collar in such manner that they can be held in position upon the frock without hooks, buttons, or like fastening devices.

10 Another object is to provide a frock with a minimum number of seams in order to reduce the time and labor required in cutting and sewing the different parts together and also to reduce the chances of ripping.

15 In order that the invention may be fully understood reference will now be had to the accompanying drawings, in which:

Fig. 1 shows one form of the garment.

Fig. 2 is a side elevation of the garment.

20 Fig. 3 is a rear elevation of the garment.

Fig. 4 is an enlarged fragmentary section on line 4—4 of Fig. 2.

Fig. 5 is a detail of one of the detachable sleeves.

25 Fig. 6 is a front elevation of a modified form of garment.

Fig. 7 is a rear elevation of the modified form of garment.

30 Fig. 8 is a diagram showing how the different parts of the modified form of garment are cut out from the material from which the garment is made.

In said drawing, 2 designates a panel forming the front portion of the garment. 35 4 designates a panel forming the rear 6 and the sides 8 of the garment. The panels 2 and 4 are preferably cut from one piece of material which is folded upon itself intermediate its ends and has neck and arm openings 3 and 5, respectively. The longitudinal margins of the panels 2 and 4 may be advantageously secured together with tape, braid, or other suitable material 10 and for the purpose of ornamentation strips 12 and 40 14, preferably of the same material as the material 10, are secured, as by stitching, to the front and rear panels. The front panel 2 is preferably provided with pockets 16, which may be advantageously fastened as by stitching to said panel by the tape 10 and 12.

45 17 designates a pair of ties which may be advantageously secured to the panel 4 by the tape 10 and when tied together serve to draw the intermediate portion of the garment snugly about the waist of the wearer.

18 designates a pair of detachable sleeves each of which has an extension 20 at its upper portion to fit within the respective arm opening 5, as more clearly shown by 60 Fig. 4. Each sleeve 18 is provided at its lower portion with a flange 22 adapted to engage the interior of the garment adjacent to the respective arm opening 5. The extension 20 of each sleeve 18 is provided 65 with a flange 24 adapted to engage over the exterior of the garment adjacent to the neck opening 3. The upper and lower margins of each sleeve are preferably trimmed and reinforced with tape 26 and 28, respectively, as shown on the drawings. The margins of the flanges 22 and 24 are also preferably trimmed and reinforced with tape 30 and 32, respectively.

70 By providing the detachable sleeves 18 with the flanges 22 and 24 as above described it is apparent that when said flanges are caused to engage the interior and exterior of the garment as above stated that they will reliably hold the respective sleeves 80 in position. The flanges 24 also constitute a two-piece collar which adds to the attractiveness of the garment.

The garment can be made from any suitable material and the opening 3 is of such 85 size as to enable said garment to be easily slipped over the head of the wearer so that openings are not necessary in the panels 2 and 4 to enable a person to don the garment.

90 By forming the back and sides in one piece seams under the arms are not necessary and hence the common annoyance from seams ripping under the arms is avoided.

95 In the modified form of garment disclosed by Figs. 6 and 7 the parts are formed in substantially the same manner as in the form disclosed by Figs. 1, 2 and 3 as is evidenced by corresponding reference characters with exponents "a," the chief differences being that instead of having the panels 2^a and 4^a formed from one piece of goods folded upon itself the goods are cut to form two separate panels, and a yoke 40 is cut from the front panel 2^a and sewed to said upper portion and the upper portion of the panel 4^a. Another difference resides in providing the arm openings with cuffs 42. The pockets 16^a, the ties 17^a and the flanges 24^a are formed from the material left from the length of goods from which the panels 2^a and 4^a are cut, so 100 that there will be but little waste of material. Likewise in the preferred form the 105 110

pockets 16, the ties 17 and the flanges 24 may be cut from the material left from the piece of goods from which the united panels 2 and 4 are cut.

Having thus described our invention, what we claim and desire to secure by Letters Patent, is:

A garment having neck and arm openings, detachable sleeves having extensions at their upper portions to project into said arm openings, a retaining element fixed to the

under portion of each sleeve and adapted to engage the interior of the garment adjacent to the respective arm openings, and retaining elements secured to the sleeve extensions and adapted to engage over the exterior of the garment adjacent the neck opening and form a collar. 15

In testimony whereof we affix our signatures.

MARY V. BRUNK.
DAISY D. HARRISON.
